JUAN VALLARO, OF MONTEVIDEO, URUGUAY.

AUTOMATIC SOUNDING-ROD.

1,286,156.

Specification of Letters Patent. Patented Nov. 26, 1918.

Application filed November 24, 1917. Serial No. 203,788.

To all whom it may concern:

Be it known that I, JUAN VALLARO, a citizen of Uruguay, and a resident of Montevideo, in the Republic of Uruguay, have invented a new and Improved Automatic Sounding-Rod, of which the following is a full, clear, and exact description.

This invention relates to sounding devices and has for an object the provision of an improved construction whereby an indicating mechanism may be arranged interiorly of the ship while the measuring or sounding rod is arranged exteriorly of the ship.

Another object in view is to provide a sounding rod pivotally connected exteriorly of the ship, an operating or power rod projecting vertically or at an angle into the ship and thereby transmitting the motion of the sounding rod to indicating means within the ship for indicating exactly the position of the rod and consequently the relative position of the keel of the ship with the bottom of the body of water in which the ship is positioned.

A still further object of the invention is to provide a sounding device with an indicating mechanism interiorly of a ship for indicating the general contour of the bottom of the river or other body of water including small elevations.

In the accompanying drawings:

Figure 1 is a partial side view of a ship with certain parts broken away together with an embodiment of the invention shown applied thereto.

Fig. 2 is a longitudinal vertical section through the upper part of the indicating mechanism shown in Fig. 1.

Fig. 3 is a sectional view through Fig. 2 on line 3—3.

Fig. 4 is a fragmentary sectional view through Fig. 2 on line 4—4.

Fig. 5 is a transverse sectional view through Fig. 2 on line 5—5.

Fig. 6 is a top plan view of a soft bottom indicating plate and part of the depth rod.

Fig. 7 is a diagram showing the arrangement of the wiring for indicating the up and down movement of the depth rod.

Referring to the accompanying drawings by numerals, 1 indicates a ship of any desired kind having a keel 2 to which the depth rod 3 is connected by means of a link 4 which is pivotally connected with the depth rod by a suitable pin and also by another pin to the keel 2. In a ship having a very low keel or

no keel at all an additional block or false keel must be provided in order that the depth rod 3 may be moved upwardly to the dotted position shown in Fig. 1 and then downwardly as far as the power rod 5 and associate parts will permit. A guide rod 6 is pivotally mounted at 7 on the keel of ship 1, and said rod is bifurcated at the lower end so that the depth rod 3 may pass therethrough and also that anti-friction wheels 8 and 9 may be provided for allowing a free sliding movement while rod 6 pivotally moves on the pin 7. There is provided sufficient play between the rollers 8 and 9 for permitting the rod 3 to move upwardly to the dotted line in Fig. 1 and downwardly a predetermined distance. At the lower end of rod 3 is a soft mud plate 10 which is rigidly secured thereto in any desired manner as for instance by bolts, said plate being preferably thin on the edges and somewhat rounded as shown in Fig. 6, whereby the same will freely pass through the water, but when the lower end of the rod 3 strikes soft mud the plate 10 will rest thereon and consequently lift rod 5 if the mud bottom is above a certain depth. Rod 5 is connected with the depth rod 3 by a pin 11 operating in the slot 12. Preferably the rod 3 is formed with a slot at the point where the slot 12 is located so that the pin 11 may pass entirely through the end of rod 5 and be journaled in the slot 12. When a high point in the bottom is engaged the lower end of the rod 3 will be moved upwardly and consequently rod 5 will be moved upwardly, while if the bottom is a considerable distance below the bottom of the ship the depth rod will move downwardly and will carry with it, by reason of its weight, rod 5 and parts connected thereto until stopped by means hereinafter fully described.

The power rod 5 extends through the bottom of the boat and through a packing box 13 rigidly secured to the boat whereby no water can enter into the boat nor into the boxing, or casing, 14 surrounding the upper part of rod 5 which is secured to the packing box 13. The boxing or casing 14 extends upwardly any desired distance, and is bent upon itself so as to extend downwardly to provide a down-leg 14' substantially parallel with the up-leg. The lower part of the casing 14 is cut away at the point where it bends and an anti-friction wheel 15 is provided for receiving a supporting chain 16. The link in general structure, is round in

cross section by reason of the fact the principal links are round and connected by similar connecting links, whereby an upward push of the rod 5 will cause the chain to move in one direction and a downward pull will cause the chain to move in the opposite direction. Each of these links is provided with a threaded aperture 17 and certain of the links provided with an aperture at right angles thereto for receiving a bolt 18 which acts as a stop under certain circumstances. If desired all of the links could be provided with apertures at right angles to the corresponding apertures 17, though this is not usually necessary. Chain 16 is rigidly connected with the shaft 5 in any suitable manner, which shaft is preferably provided with a flange 19 at the upper end larger than the aperture through which the shaft or rod 20 passes whereby the shaft or rod cannot move down beyond a certain point, and a brake 21 is provided, preferably near the wheel 15, said brake being formed with a shoe 22 adapted to press against the various links 25 16' as they pass, said shoe being continually pressed by a spring 23 held under tension by an adjusting screw 24, whereby any pressure may be provided for preventing the upward movement of the chain caused by 30 the pressure of water against the rod 3 when the vessel is moving. The down-leg 14' of the casing is provided with a slot 25 through which the stop 26 may extend as shown in Fig. 5 when applied to any of the links 16'. 35 A chain or cable 27 is connected to the end link 16' as shown in Fig. 1 and then passes over pulley 28 to a drum 29 whereby the operation of drum 29, either manually or by machinery, chain 16 may be pulled and the 40 depth rod 3 moved upwardly to the dotted position shown in Fig. 1, or lowered to any desired extent. Arranged at one side of the down-leg 14' of the chain casing is a supporting arm or bracket 30 made of any desired material, preferably of metal, said bracket being provided with upstanding members 31 and 32, which upstanding members have longitudinal grooves 33 and 34 for receiving and guiding the cross bar 35 45 which carries the pin 36. The cross bar 35 is of such thickness as to freely slide in the guides 33 and 34, but sufficiently tight to remain in any position in which it is placed. This is very desirable as the stop 26 extends 50 across the bracket 30 and moves the pin 36 from time to time as hereinafter fully described. Stop 26 is provided with a resilient finger or contact member 37 which normally presses against the insulated button 38, 55 which button is frictionally held in any of the apertures in any of the blocks 40.

From Figs. 1, 2 and 4 it will be seen that there is provided a number of blocks, preferably the same number as there are lamps 60 41 in the bank of lamps 42. These various

blocks are spaced apart as shown in Fig. 4 and insulated from the surrounding members, and when the insulating button 38 is used they are in addition insulated from the finger 37, which finger is rigidly secured in 70 any desired manner to the pin 36. As above stated there is one lamp 41 for each block 40 and in addition there is a lamp for the contact members 43 and 44 which members are rigidly secured to the casing 14 in 75 any desired way. These are intended as vibrating contacts whereby when the rod 3 is scraping along on a hard bottom a sufficient vibration will be created for causing this contact to engage and disengage intermittently and thereby light up intermittently one of the lamps 41. Preferably a bell 41 is provided in the circuit so that whenever any of the lamps are lighted the bell will be sounded. 80

In operation after the parts have been properly positioned on a ship the operator releases the drum 29 until the depth rod 3 has been lowered to the desired extent, either for its full distance or part of the distance, and the bolt 18 is inserted into one of the bolt holes or apertures 18', the said bolt extending through an opening in casing 14 as shown in Fig. 2 whereby the chain to which it is secured cannot move to any considerable extent. As the boat is propelled the pressure of the water will have a tendency to raise the rod 3 and to overcome this the brake 31 is operated until this tendency has been completely overcome by friction of 90 the brake on the chain. This is not sufficiently great for preventing the chain from moving when the bottom has been engaged, but merely sufficient for preventing the water pressure from raising the chain. In 95 case the downward pull on the rod 3 and associate parts is undesirable a weight 45 could be connected with the end of the chain carrying cable 27 by applying suitable bolts in some of the apertures 17, and then supporting weights thereon until a proper balance is secured. After this has been done bolt 18 is removed and placed in the highest aperture 17 disclosed through slot 25 where the rod 3 is positively prevented 100 from moving downward, but is provided a free upward movement when striking the bottom. After bolt 18 has been thus placed in position stop 26 is placed in a desired position, for instance, the extreme depth to 105 which the rod 3 is permitted to go, as for instance 8 fathoms, indicated by number eight on one of the blocks 40. The insulating button 38 is placed in the block 40 carrying number eight after which the bar 35 110 with pin 36 is moved upward to block carrying number eight and the finger or contact member 37 placed in the insulating button. This insulating button is merely for the purpose of preventing the ringing of 115 120 125 130

the bell when rod 3 is in its extreme lowered position. After the parts have been arranged as just described the boat may then proceed to the place where it is desired to survey or ascertain whether or not a sufficient depth is provided for the desired purpose. When this survey is taking place if it should happen the lower end of the rod 3 merely drags along over a hard surface the vibration thereof would cause the contact members 43 and 44 to intermittently engage and consequently intermittently light one of the lights, which is preferably a red light, so as to indicate what is happening. 10 In case a hard surface should be engaged above the desired depth rod 3 together with the power rod or shaft 5 would be moved upwardly and chain 16 would also be moved notwithstanding the brake 21. As soon as the chain began to move stop 26 would press against the pin 36 and move the same together with the finger 37 until the finger 37 moved off the button 38 and engaged block 40 carrying number eight. If 15 the movement was considerable the finger or contact member 37 would slide over several blocks and stop only when the upward movement of rod 3 closes. When this occurred the rod 3 would move downwardly 20 and would carry the other parts with it until it began to assume a former position with the stop 26 opposite the block 40 carrying number eight. However, the pin 36 would remain at the place to which it had 25 been moved and would complete a circuit for continuously sounding the bell and lighting one of the lights 41. As soon as the proper information has been noted on a record the pin together with the finger 37 and associate parts are moved back to their 30 former position manually and the end of finger 37 placed on the button 38 as shown in Fig. 4. As soon as a high point in the bottom was again struck the same thing 35 would reoccur. It is, of course, evident that the parts may be moved only a short distance or moved fully up to a position against the bottom of the boat and this movement would be conveyed to the stop 40 26 and associate parts.

The soft bottom indicator plate 10 acts in the same manner as the rod 3 in operating the chain 16 and associate parts, and that rod 3 must extend downwardly into 50 the soft bottom sufficiently for causing the plate to produce a sufficient resistance to raise the shaft 5.

What I claim is:

1. A sounding rod of the character described comprising a depth rod, means for pivotally connecting one end of the rod to the bottom of a ship so that the rod will extend substantially longitudinally of the ship, means for guiding the rod in its pivotal movement, a power rod connected with the 55 said first mentioned rod, said power rod extending through the shell of the ship to the interior, and means on the interior of the ship operated by the up and down movement of the power rod for indicating the 70 distance between the lower end of the depth rod and the bottom of the ship.

2. In a sounding rod of the character described, the combination with a ship of a depth rod, a link pivotally connected with 75 one end of said depth rod and also pivotally connected with the bottom of said ship, a power rod connected to said depth rod near the lower end of the depth rod, said power rod extending through the shell of 80 the ship, means pivotally connected with said ship and straddling said depth rod for preventing movement thereof, and means connected with said power rod interiorly of the ship for disclosing the extent of the up 85 and down movement of the depth rod.

3. A sounding rod of the character described comprising a depth rod pivotally connected to the bottom of a ship when in use, a power rod or shaft extending through 90 the bottom of the ship and connected at its lower end with said depth rod, a flexible member connected to said power rod, means for guiding said flexible member so that the same may move in a certain path as said 95 power member is moved upwardly and downwardly, means operated by said flexible member for indicating the amount of movement of said depth rod, and signal members operated by said depth rod. 100

4. A sounding rod of the character described, comprising a depth rod pivotally mounted on the bottom of a ship when in use, a power rod connected with said depth rod extending into the interior of the ship, 105 a tubular member connected with the ship and extending upwardly and then downwardly so as to provide parallel guides, one of said guides having a slot for almost its entire length, a flexible member connected 110 with said power rod and positioned in said tubular member, a plurality of insulated blocks arranged adjacent the tubular member having the slot therein, a sliding contact member arranged adjacent said blocks, 115 means connected with said flexible member extending over said blocks so that when said depth rod is moved upwardly the flexible member will be moved so that the stop operating said sliding contact member will move 120 the same over said blocks in proportion to the movement of the depth rod, and an electrically operated signal member connected with each of said blocks so as to give a signal when said contact member moves over the 125 respective blocks.

5. In a sounding rod of the character described, the combination with a ship of a depth rod pivotally connected at one end to the bottom of said ship, a power rod ex- 130

tending from near the opposite end of said depth rod and projecting into the interior of said ship, a packing member surrounding said power rod as it enters the ship, a 5 **U**-shaped tubular guiding rod having one end connected with said packing member while the opposite end is provided with a slot extending upwardly a predetermined distance, a flexible member connected with 10 said power rod extending substantially the full length of said **U**-shaped member, a cable connected with the end of said flexible member whereby the same may be pulled and the depth rod moved upwardly to a position 15 substantially parallel to the bottom of the ship, signal and indicating means, and a mechanism operated by said flexible member for actuating said signal and indicating means.

6. In a sounding rod of the character described, the combination with a ship of a contact depth rod connected with the bottom of the ship, a power rod connected with said depth rod extending into the ship, a flexible member connected with said power 25 member, a signaling means operated by said flexible member for indicating the depth of said depth rod, and an adjustable brake acting on said flexible member for overcoming the pressure of the water acting on the 30 depth rod.

In testimony whereof I have signed my name to this specification in the presence of two subscribing witnesses.

JUAN VALLARO.
